UNITED STATES PATENT OFFICE.

HENRY PITT ROBERTS, OF BOSTON, MASSACHUSETTS, ASSIGNOR TO
CHARLES F. HOWE, OF BOSTON, MASSACHUSETTS.

SAFETY-ENVELOP.

No. 811,092.

Specification of Letters Patent.

Patented Jan. 30, 1906.

Application filed August 29, 1904. Serial No. 222,512.

To all whom it may concern:

Be it known that I, HENRY PITT ROBERTS, a citizen of the United States, residing in Boston, in the county of Suffolk and State of Massachusetts, have invented certain new and useful Improvements in Safety-Envelops, of which the following, taken in connection with the accompanying drawings, is a specification.

This invention relates to envelops which are so constructed that after sealing an attempt by any one to open the envelop may be detected.

Many types of safety-envelops have been proposed; but the various devices which have been suggested have heretofore failed to meet prevailing conditions. Any fairly careful person in a reasonably short time can open envelops now in use, and the envelop can be resealed so that the attention of the average correspondent will not be attracted.

The object of this invention is to furnish an envelop that will clearly show the effects of any disturbance of the seal and accomplish this without increasing the cost of the article.

Believing that one general fault of previous efforts to make a safety-envelop has been that the unusual construction has attracted the attention of the party handling the mail and a little study has suggested some easy way of avoiding or overcoming the supposed safety device, I have concealed my safety device so that the first notice thereof obtained will be after having so damaged the envelop that detection is certain. Then the clerk must either reseal the envelop without disturbing its contents or, taking the contents, run great risk of discovery. It will soon become well known in the postal service that dangerous envelops are in the mails, and this will deter mail-clerks from touching envelops of any type, and thus increase the safety of mail correspondence.

The invention consists in cutting the material of the envelop to form small tongues along all or a selected portion of the line of sealing, and the said tongues may be so located that the gummed flap of the envelop will cover and conceal the said tongues from view.

The invention also consists in forming the tongues so as to present a large portion of their surface to the gummed flap and in connecting the tongues to the material of the envelop by comparatively narrow necks, so the

necks may break when touched by a tool or, if strained, before the tongues can be worked free from the gummed flap.

The invention further consists in arranging the necks of the tongues in alternation in the line of sealing, and in various features of novelty and in the selection and arrangement of parts that will be particularly described.

The drawings show in Figure 1 a rear view of my safety-envelop closed for mailing; Fig. 2, a rear view of the envelop before sealing; Figs. 3 and 4, some shapes used for tongues, and Fig. 5 modifications of the invention.

In general appearance the envelop is of ordinary type and may have an end, as *a*, folded over and secured by the pasted lap-joint *b* to the end *c*. The bottom piece *d* may be folded over the edges *e* of the ends *a* and *c* to form the lap-joint *f*, and this lap-joint may be gummed so the bottom piece *d* may be attached to the ends *a* and *c*, as usual. The sealing-flap *g* can also be folded over in any common way so it may cover the ends *a* and *c*, as well as usually the tip *h* of the bottom piece *d*. The flap *g* is gummed along the margin *i* for sealing, as now practiced, all the above being the ordinary and well-known form of envelop. It is said to be common practice to open envelops at the line of sealing by inserting some thin smooth tool, as the small end of a penholder or a blade or a stiff needle, at the sealed line and by turning and advancing the instrument to pry up the sealed flap from the back of the envelop, this being aided, if convenient, by moisture, steaming, &c. The process is ordinarily quite rapid if the operator is skilful, and the feature to be noticed is that the tool is usually advanced in the same general direction. Now to render such an envelop secure I form tongues *j* in the ends *a* and *c* to register with the middle of the gummed surface *k* of the flap *g* or the bottom *d*. The tongues are illustrated more fully in Figs. 3 and 4, being formed by making incisions in the paper or other material of the envelop or by cutting out sections to leave the tongues *j* entirely clear except at the necks *l*, which unite the tongues with the material of the envelop.

A characteristic feature of the tongues consists in the large surface exposed to the gum of the flap and the neck of greatly-reduced section connecting the tongues with the material of some portion of the envelop. This

neck is purposely made narrow, so it may break if an attempt is made to release the tongue from the gum of the flap. The scroll form furnishes within a small area a very long neck, which is a further advantage, and it is found also to be useful to form sharp angles and recesses in and about the tongues to cause the tool to tear the envelop. The tongues are not usually set facing all the same way, a desirable arrangement being shown at Fig. 2, in which the tongues alternate in position along the gummed line. This causes a tool advancing in one general direction to pass first above and then below a neck, either of which may be twisted by the tool the wrong way and break. The tongues are frequently spaced much nearer each other than appears from the drawings and do not always extend the entire length of the gummed joint, being often grouped about the tip *m* at the middle of the flap *g*, which covers the tip *h* of the bottom *d*.

Sometimes the sealing-flap, together with the ends *a* and *c*, have tongues cut to register one over the other, and the tongues are arranged so the necks of the tongues of the flap are at the sides opposite the necks of the tongues of the ends *a* and *c*, the tongues adhering or interlocking with each other. Now if an attempt is made to separate tongues so adhering the neck at one or the other side of the tongues is likely to be broken by the tool in the hands of the operator.

In use the sender should note that all the tongues in the ends *a* and *c* are in place, then moisten the gummed flap *g* and seal as usual. When such an envelop is received, upon tearing it open if some of the necks of the tongues are broken or the tongues overlap their spaces, as may be seen from the inside of the envelop, then the envelop has probably been opened.

The principal feature of advantage which my improvement possesses over other envelops of the same class is, first, that the tongues are concealed from view by the overlying flap, so that it is impossible for a person who intends to surreptitiously open the letter to know that any means has been provided to detect unauthorized opening or tampering with the envelop; secondly, the tongues being provided with narrow necks it will be practically impossible to open any of the flaps of the envelop without tearing the tongue at the neck thereof, and, thirdly, if any of the tongues are torn in this manner it will be impossible to paste the flap down again in such manner as to avoid a betrayal of the fact that the envelop has been opened, since upon inspecting the interior of the envelop the broken line where the neck of the tongue has been severed will be apparent at a glance.

Having described my invention, I claim and desire to secure by Letters Patent of the United States—

An envelop comprising a body, end flaps, and a bottom flap, and a main sealing-flap, the end flaps being provided with a series of tongues lying wholly within the edges of the flaps and entirely covered by the bottom flap and main sealing-flap when said flaps are sealed onto the end flaps, the said tongues being united to the envelop by narrow necks materially less in section than the section of the tongues, and the tongues being so disposed that the alternating tongues project in opposite directions.

In testimony whereof I have hereunto subscribed my name this 13th day of August, A. D. 1904.

HENRY Pitt ROBERTS.
